(57) **CLAIM**

The ornamental design for a phone case, as shown and described.

DESCRIPTION

FIG. 1 is a perspective view of a phone case showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof in a use state; and,

FIG. 9 is a perspective view thereof in another use state.

The broken lines in the drawings illustrate portions of the phone case that form no part of the claimed design. Additional broken lines in FIG. 9 showing a hand, depict environmental subject matter and form no part of the claimed design.

1 Claim, 8 Drawing Sheets(56)
